(57) **CLAIM**

The ornamental design for a food container, as shown and described.

DESCRIPTION

FIG. 1 is a perspective view thereof of a food container, embodying my design;

FIG. 2 is a top plan view thereof;

FIG. 3 is a bottom plan view thereof;

FIG. 4 is a side elevational view thereof, the opposite side being identical;

FIG. 5 is a front end view, thereof;

FIG. 6 is a rear end view thereof; and,

FIG. 7 is a perspective view thereof, showing the cover in a partially open position.

The broken lines are for illustrative purpose only and from no part of the claimed design.
